UNITED STATES PATENT OFFICE.

CHARLES HENRY PETTIGREW, OF HAYES, ENGLAND, ASSIGNOR TO THE GOSS PRINTING PRESS COMPANY, OF CHICAGO, ILLINOIS, A CORPORATION OF ILLINOIS.

PLATE-CASTING MACHINE.

1,072,158.

Specification of Letters Patent.

Patented Sept. 2, 1913.

Application filed September 20, 1912. Serial No. 723,283.

To all whom it may concern:

Be it known that I, CHARLES HENRY PETTIGREW, a citizen of the United States of America, residing at Hayes, in the county 5 of Middlesex, England, have invented new and useful Improvements in Plate-Casting Machines, of which the following is a specification.

This invention relates to machines for 10 casting stereotype plates for use in rotary cylinder printing presses in which the matrix holder or drag is movable with respect to the cope by means of suitable handles, so that after the stereotype plate has been cast, 15 preferably in a vertical position, the drag may be moved into a horizontal position for the purpose of conveniently removing the stereotype plate therefrom.

According to this invention the trunnion 20 rollers by which the drag is supported upon the supporting surfaces and the guiding rollers which coöperate with the guiding surfaces to effect a turning of the drag into horizontal position are so arranged that the 25 guiding surfaces can be made as continuations of the supporting surfaces, thus considerably simplifying the construction of the machine. For this purpose the trunnion rollers and the guiding rollers are so situated on the drag that a line joining their centers, lies in a horizontal plane when the drag is in its vertical position. The supporting and guiding surfaces in the side frames of the machine may be in the form of 30 slots so shaped that they are horizontal at their upper part and terminate at their outward or rearward ends in downwardly curved portions. The distance apart of the 35 said trunnion rollers and guiding rollers is such, and the curvature of the guiding slots 40 so chosen, that when the drag is moved away from the cope, both the trunnion rollers and the guiding rollers will travel in a horizontal direction on the supporting surface until 45 the guiding rollers reach the downwardly curved portions of the slots, whereupon the drag will be caused to turn about the axis of the trunnion rollers while the latter continue to move along the horizontal portion 50 of the slots, the turning movement of the drag continuing until the guiding rollers reach the ends of the downwardly curved portions of the said slots and bring the drag to rest in its horizontal position.

55 In order that the said invention may be

clearly understood and readily carried into effect, I will describe the same more fully with reference to the accompanying drawings in which:—

Figure 1 is a side elevation of the machine 60 showing the drag in the vertical or closed position *i. e.* the position in which the stereotype plate is cast. Fig. 2 is an end view of the machine as seen from the right of Fig. 1; and Fig. 3 is an end view similar 65 to Fig. 2 but shows the drag in the horizontal or open position *i. e.* the position in which the stereotype plate is removed. Fig. 4 is a central vertical section through the drag. 70

A is the cope or stationary part of the mold and B is the drag. B² indicates a circular plate loosely seated in the lower end of the drag, the upper beveled edge of which forms the bottom wall of the casting box. 75 B' indicates handles mounted on said plate B².

The cope is mounted on the base A¹ which carries the vertical side frames C, bolted together by the transverse members C¹, C¹. 80 These side frames are formed with the slots c c' which constitute the supporting and guiding surfaces for the trunnion rollers a and the guiding rollers a'. The trunnion rollers a are adapted to travel along the 85 horizontal portion c of the said slots and the guiding rollers a' are carried at the extremities of brackets or arms a² extending rearwardly from the drag in a position in which the axis of the said rollers a' lie in 90 the same horizontal plane with the axis of the rollers a when the drag is in the vertical position.

The drag B is held in its vertical position 95 relative to the cope A by means of brackets E and F fixedly mounted on transversely-extending shafts G and H, respectively, which are suitably journaled upon the cope A. Each of these brackets is provided with a transversely-extending flange I adapted to 100 engage a stud or roller J in appropriate position upon the drag B when said drag is rocked about its shaft as hereinafter described.

D indicates levers mounted upon the 105 shaft G.

K—L indicate rock arms mounted upon the shafts G and H, respectively, connected at their outer ends by a link M, whereby 110 said shafts and therefore the brackets E and

F are caused to swing in unison. As will be readily understood from an inspection of Fig. 1, when the levers D are swung forward and downward from the position 5 shown in that figure, the brackets E and F are swung into such position that the studs J are free to move to the right in said figure. At any time when the drag B is in the vertical position shown in Fig. 1, which 10 position it can assume fully only when the levers D have been turned to their lowered position, the drag can of course be locked tightly against the cope A by a stroke of the levers D to the position shown in that figure, the 15 studs J being engaged by the flanges I of the brackets.

In order to turn the drag B into the horizontal or open position, a pull is exerted thereon rearwardly by means of the handles 20 b whereby the rollers a a' are caused to travel along the horizontal portion c of the slots in the side frames C until the guiding rollers a' enter the curved portion of the said slots whereupon these rollers are caused 25 to descend in the curved portion of the slots and in so doing cause the drag to be turned about the axis of the trunnion rollers a into the position shown by the dotted lines in Fig. 1. From this position the drag may be 30 returned to the vertical position by exerting a pull upon the handles b' thereby causing similar movements to occur in the reverse order to that above described.

What I claim and desire to secure by Letters Patent of the United States is:—

1. In a plate casting machine, the combination of a frame, a cope mounted therein, and a drag provided with guiding means and with supporting means, said frame comprising guides with which the guiding means of said drag have sliding engagement and comprising also supports with which the supporting means of said drag have

sliding engagement, said guides and said supports being continuations of each other. 45

2. In a machine for casting stereotype plates and the like, the combination with the cope, the movable matrix holder or drag and the trunnion rollers and guiding rollers on said drag, of surfaces for guiding and 50 surfaces for supporting said rollers, so disposed relatively to each other that the guiding surfaces are continuations of the supporting surfaces.

3. In a machine for casting stereotype 55 plates and the like, the combination with the cope, the movable matrix holder or drag and the trunnion rollers and guiding rollers on said drag, of side frames having guiding and supporting surfaces for said rollers, 60 made in the form of slots which are horizontal at their upper parts and terminate at their outward or rearward ends in downwardly curved portions so disposed relatively to each other that the guiding surfaces are continuations of the supporting 65 surfaces.

4. In a machine for casting stereotype plates and the like, the combination with the cope, the movable matrix holder or drag 70 and the trunnion rollers and guiding rollers on the said drag, of side frames having continuous guiding and supporting slots for said rollers and brackets extending rearwardly from the drag for carrying the guiding rollers in a position in which their axis lies in the same horizontal plane with the axis of the trunnion rollers when the drag 75 is in the vertical position.

In testimony whereof I affix my signature 80 in presence of two witnesses.

CHARLES HENRY PETTIGREW.
